EDWARD WELLS, OF NEW HAVEN, CONNECTICUT, ASSIGNOR TO WELLS, CRITTENDEN & CO., OF SAME PLACE.

Design No. 4,322, dated August 30, 1870.

DESIGN FOR CARRIAGE-BOOT.

The Schedule referred to in these Letters Patent and making part of the same.

To all whom it may concern:

Be it known that I, EDWARD WELLS, of New Haven, in the county of New Haven and State of Connecticut, have invented a new Design for Carriage-Boot; and I do hereby declare the following, when taken in connection with the accompanying drawing and the letters of reference marked thereon, to be a full, clear, and exact description of the same, and which said drawing constitutes part of this specification, and represents in—

Figure 1, a side view;

Figure 2, a top view; and in

Figure 3, a section on line $\alpha\alpha$ of fig. 1.

This invention relates to a design for that part of a coach or carriage known as the boot, that is to say, the support for the driver's seat, and under which the fifth-wheel or connecting device for the forward axle is arranged; and

The invention consists in the peculiar configuration and shape of the boot, as more fully hereafter described.

α is the upper surface to which the seat is fixed.

b , the foot-board.

c , the lower surface, to which the forward axle-attachment is secured, and from which the boot extends back to the carriage, shown as broken off at d .

Upon the upper side, from the seat down toward the carriage-body, the boot is formed, commencing at an oval shape, as at a , and running into nearly a semi-circular form on line $\alpha\alpha$, thence into an oval or nearly flat shape at the carriage-body.

This design or shape gives to the boot a neat and tasteful appearance, which has not heretofore been produced.

I claim as my invention—

The design for carriage-boot, substantially as herein described and shown.

EDWARD WELLS.
